GARMENT IDENTIFICATION

Wentworth S. Hines, Burlington, N. C.

Application March 10, 1939, Serial No. 261,075

12 Claims.

(Cl. 93—88)

My invention relates to the identification of garments in cleaning and pressing establishments, and has among its objects and advantages the provision of an improved labeling device. The invention embodies mechanism provided with a roll of tape together with means for advancing the tape in predetermined lengths and severing the same to provide labels which are simultaneously stapled to the garments and automatically numbered for identification purposes.

In the accompanying drawings:

Figure 1 is a plan view of a machine in accordance with my invention;

Figure 2 is a sectional view along the line 2—2 of Figure 1;

Figure 3 is a perspective view of a portion of a garment illustrating one of the numbered labels stapled to the garment;

Figure 4 is a sectional view along the line 4—4 of Figure 1;

Figure 5 is a view taken from the position indicated by line 5—5 of Figure 2;

Figure 6 is a sectional view taken substantially along the line 6—6 of Figure 7;

Figure 7 is a view taken along the line 7—7 of Figure 4; and

Figure 8 is a view taken along the line 8—8 of Figure 7.

In the embodiment selected to illustrate my invention, I make use of a base 10 to which I attach a side wall 12 and a front wall 14. To the upper margins of the walls 12 and 14 I position a work support or table 16, which is made secure by screws 18. Wall 12 has its lower edge resting on the base 10, and a plate 20 is welded to the wall 12 and is fixedly related to the base by screws 22. Wall 14 is secured to the base by screws 24.

A roll 26 of tape 28 is rotatively mounted on a shaft 30 mounted on a bracket 32 bolted at 34 to the side plate 12. Upon the shaft 30 I mount a compression spring 36 arranged to bear against the reel 38 which carries the roll 26 to restrain the same from accidental unwinding. The spring is maintained under tension by a wing nut 40 threaded to the shaft 30, the latter being fixedly related to the bracket 32.

Web 28 passes between a feed roll 42 and a pressure roll 44. Figure 7 illustrates the feed roll 42 as being provided with abrasive coated surfaces 46. Immediately above the rolls 42 and 44 I position a web guide 48, which includes a throat 50 facilitating entry of the web. I groove the feed roll 42 at 52 to provide accommodation for the lip 54. Figures 4 and 8 illustrate the normal

position of the guide 48 at which time the web 28 projects partly across the work support 16 in angular relation therewith. The projecting end 56 of the tape is spaced some distance above the face of the work support so that the garment 5 may easily be slipped underneath the tape preparatory to cutting, attaching and numbering the label to be cut from the tape.

One wall of the guide 48 is pivotally mounted on a shaft 58, and the guide is yieldingly urged to the normal position of Figures 4 and 8 by reason of a spring 60 convoluted upon the shaft with one end bent underneath the guide and the other end secured to the side wall 12. Roller 44 is loosely mounted on a shaft 62, and the shaft is fixedly related to a support 64 pivoted at 66 intermediate its ends to the side wall 12, see Figure 6. Shaft 62 is located at one end of the support 64, while to the other end of the support I connect a tension spring 68 by a screw 70 and anchor the other end of the spring to the side wall 12 by a screw 72. Thus the roller 44 is spring urged in the direction of the roller 42 for pressing the web 28 between the two rollers so as to impart positive movement to the web as the roller 42 is rotated. Upon the core 74 of the roller 44 I mount a rubber sleeve 76 to increase the tractive properties of the roller.

To one end of the roller 42 I attach a ratchet wheel 78. The ratchet wheel is keyed to the roller at 80, see Figure 8, and the two parts rotate as a unit. The roller and the ratchet wheel are loosely mounted on a shaft 82 fixedly related to the wall 12. Roller 42 is constrained for rotation in one direction only through the medium of a latch bar 84 pivotally mounted intermediate its ends on a pivot 86 threaded into the wall 12. One end of the latch bar is arranged to have successive engagement with the teeth 88 of the ratchet wheel 78, and that end of the bar is yieldingly urged against the ratchet wheel by reason of a tension spring 90 connected at 92 with the bar and at 94 with the side plate 12. Thus according to Figure 6, the wheel 42 is free to rotate in the direction of the arrow 96, and means for rotating the wheel comprises a hook 98 at one end of a bar 100 having its other end pivotally connected upon a pin 102 fixedly related to a disc 104, see Figures 7, 4 and 6. Hook 98 is yieldingly urged against the ratchet wheel 78 by reason of a tension spring 106 having one end connected at 108 with the bar 100 and its opposite end connected at 110 to the side wall 12.

Disc 104 is bored for the reception of one end of a shaft 112, which shaft is made secure by 53

- reason of a set screw 114, see Figure 7. The other end of the shaft 112 is anchored in a brake cylinder 116 fixedly connected with a shaft 118 driven by a speed reducer 120, see Figures 1 and 8. 5 Speed reducer 120 may comprise any one of the many standard types and need not be described in further detail. Suffice it to say that the speed reducer is driven by an electric motor 122 bolted at 124 to the base 10. A cam bar 126 is also 10 fixedly related to the shaft 118 by a set screw 128. Thus the disc 104, the brake cylinder 116 and the cam bar 126 rotate as a unit, and the direction of rotation is indicated by the arrow 130. Accordingly, pin 102 and shaft 112 function as 15 cranks because of their eccentric relation with respect to the axis of the shaft 118.
- Motor 122 is controlled by a conventional switch 132, see Figure 7, which switch includes the usual manually actuated trip 134 extending 20 into a bore 136 in a plunger 138 positioned vertically and slidably in a bore 140 in the work support 16. I provide a flanged end 142 on the plunger 138 to facilitate manual thrust downwardly of the plunger for closing the switch 132. 25 A bracket 144 is connected with the switch and is bolted to the work support 16 for supporting the switch. Figure 7 illustrates the switch in its open position, which is also true of Figure 4.
- One end of a rod 146 is threaded into the 30 lower end of the plunger 138 and its lower end is provided with a bend 148 which extends loosely through an opening in one end of a bar 150 pivotally mounted intermediate its ends on a shaft 152 carried by a bracket 154 screwed to 35 the base 10, as at 156 in Figure 7. To the end of the bar 150 opposite the rod 146 I provide a right-angular cam pin 158 which is arranged in the path of the cam face 160 on the cam bar 126, see Figures 4, 6 and 7. Pin 158 lies in the 40 clear of the cam face 160 when the bar 150 is positioned according to Figures 4 and 7, at which time the motor switch 132 is open. Figure 4 also illustrates the normal position of the cam bar 126, which position is determined by reason of 45 a brake pad 162 anchored to one end of a brake bar 164, which is pivotally connected at one end with a bolt 166 threaded into the side wall 12. Brake pad 162 is urged into frictional relation with the brake cylinder 116 by reason 50 of a compression spring 168 having one end positioned on the base 10 and its other end lying loosely in a bore 170 in the brake bar 164. The latter is provided with a threaded bore 172 into which an adjusting screw 174 is threaded to 55 position its inner end against the pressure disc 176 abutting the upper end of the compression spring 168.
- Precise frictional relation between the brake 60 pad 162 and the brake cylinder 116 is attained through adjustment of the screw 174, which screw is provided with a head 178 to permit manual adjustment thereof or adjustment through the medium of a screw driver inserted in the slot 180. I provide the screw with a lock 65 nut 182 to have frictional relation with the brake bar 164 to hold the screw against accidental displacement so as to maintain accurate adjustment of the screw.
- The circuit through the motor 122 is closed 70 by exerting downward pressure on the plunger 138. Such downward pressure will snap the trip 134 to its closed position and at the same time pivot the bar 150 for bringing its pin 158 upwardly into the path of the cam face 160. Shaft 75 118 is rotated one complete revolution each time

the plunger 138 is depressed, and during such rotation the roll 42 will be rotated in the direction of the arrow 96 for advancing the web 28. Figure 4 illustrates the position of the cam face 160 at the time that the plunger 138 is depressed, after which the cam bar 126 is rotated in the direction of the arrow 130. During such rotation the cam face 160 is brought into camming relation with the pin 158 for pivoting the bar 150 and elevating the plunger 138 to bring the trip 134 back to its normal or open position. Conventional switch trips are influenced by spring tension in the two positions of the trip in sufficient degree to yieldingly support the plunger 138 in either of its two positions. It 15 will thus be seen that the circuit through the motor 122 is closed during partial rotation of the shaft 118. Figure 6 illustrates the cam face 160 as having passed beyond the pin 158, at 20 which time the switch 132 is open. The momentum of the motor armature and moving parts is such as to continue rotation of the shaft 118 against the braking action of the brake pad 162 until the cam block 126 has been moved back to its normal position of Figure 4. 25

In Figure 4, the hook 98 is in engagement with one of the teeth 88, while Figure 6 illustrates the hook 98 as having been pushed beyond the adjacent tooth 184 but the hook is prevented from engagement with the tooth 186 because of the 30 edge 188 on the bar 100 which engages the teeth 88 in such manner as to hold the hook 98 out of reach of the second tooth it may pass, so that on reverse movement of the bar 100 the hook will be brought into engagement with the tooth 35 184 for rotating the roll 42 one tooth at a time, which rotation advances the web 28 one label length at a time.

In attaching the label, the garment is placed on the work table 16 and is advanced until 40 stopped by the backing plate 190. The garment is inserted underneath the web extension 56 and the plunger 138 depressed. As the motor is started, rotation of the brake cylinder 116 will carry with it the shaft 112 to which I pivotally 45 connect the lower end of a link 192, which extends upwardly and is pivotally connected at 194 with a bar 196 pivotally connected at 198 to the side wall 12. To the forward end of the bar 196 I mount a numbering device 200 normally positioned as illustrated in Figure 4 slightly above the tape extension 56 so that the garment may easily be placed in position. Numbering device 200 may comprise any one of the many standard types in which the number is changed 50 a digit at a time. Broadly the device 200 includes a pressure plate 202 mounted on a yoke 204 shifted upwardly relatively to the body 206 of the numbering device for uncovering the number wheels for inking purposes as well as to 60 bring the number wheels into printing relation with the label on the garment. Plate 202 includes an opening 208 in its face for accommodating the number wheels 210 as the device 200 is moved downwardly on the garment. 65

I prefer to mount the numbering device 200 on a bar 212 positioned on the bar 196 and secured thereto through the medium of a bolt 214. Between the washer 216 underneath the head of the bolt 214 I position a cushioning 70 washer 218 so that the bar 212 may move short distances from the bar 196 to cushion the impact of the numbering device 200 as it is pressed against the garment. Thus the cushioning washer 218 provides compensation for garments 75

and goods of different thicknesses so that setting of the numbering device 200 to operate on the thinnest material will also accommodate the heavier goods.

5 Bar 212 is restrained from lateral displacement relatively of the bar 196 by reason of a pin 220 fixedly related to the bar 196 and extending into a slot 222 in the bar 212, see Figure 1. The numbering device 200 includes a shaft 10 224 positioned in a bore 226 in the bar 212, which bore is intersected by the slot 222 so that the shaft 224 may be clamped firmly in place through tightening of the screw 228. The inner end of the slot 222 terminates in a bore 230 for weakening the bar to such a degree as to permit effective clamping thereof on the shaft 224.

15 Rotation of the brake cylinder 116 in the direction of the arrow 130 of Figure 4 will exert a pull on the link 192 for pivoting the bar 196 20 downwardly, which brings the plate 202 into pressure relation with the garment on the work support 16 for printing a number on the web extending across the garment. Figure 6 illustrates the numbering device 200 in pressure relation with the garment, at which time the web 28 has been advanced slightly beyond the position 25 illustrated by the extension 56 in Figure 4, and severed at 232 to provide a label 234, see Figure 6. Work table 16 is provided with a semi-rigid cushioning pad 236 lying directly underneath the number wheels 210 of the counting mechanism 200.

20 As the numbering device 200 is brought into pressure relation with the garment 238 on the work table 16, a pin 240 engages the impact head 242 of a stapling device 244 pivotally mounted on a shaft 246 carried by ears 248 associated with a bracket 250 anchored to the side plate 12. Stapling unit 244 may comprise any one of the 25 many suitable types of conventional stapling mechanisms and need not, therefore, be described in more detail. Figure 6 illustrates an anvil 252 mounted on the work support 16 for cooperation with the stapling mechanism 244 in the usual 30 manner.

25 Stapling mechanism 244 has its forward end resting on a web severing blade 254, see Figures 2 and 4, and the backing plate 190 is slotted at 256, see Figure 7, to provide accommodation for the forward end of the stapling mechanism as it is 35 swung downwardly on the anvil 252, as illustrated in Figure 6. Figure 2 best illustrates the blade 254. The blade is pivoted at 258 to the edge 260 of the work support 16. Normally the blade 254 40 is in the position illustrated in Figure 2, at which time the stapling mechanism 244 rests on the blade and is supported thereby in the position of Figure 4.

30 To the blade I fixedly connect a right-angular arm 262 to which one end of a tension spring 264 is connected, the opposite end of the tension spring being connected to an arm 266, see Figures 1 and 2. I prefer to provide the edge 260 of the work support 16 with a stationary blade 268, see 45 Figure 2. Blade 254 has a cutting edge 270 arranged in shearing relation with the stationary blade 268 for severing the web 28 as the stapling device 244 is pivoted downwardly. Figure 50 8 illustrates a flat spring 272 as having one end fixedly secured at 274 to the bracket 250 and its other end lying on the web guide 48, with the 55 stapling device 244 provided with a laterally extending finger 276 arranged to press downwardly on the spring 272 for pivoting the web guide 275 48 downwardly. Thus the extension 56 is moved

downwardly on the garment as the numbering device 200 and the stapling device 244 are pivoted downwardly.

5 Shaft 58, upon which the web guide 48 is pivotally mounted, has one end clamped underneath a plate 278 and its other end supported in a socket 280 carried by a bar 282 screwed to the bracket 250. The convoluted spring 60 has one end anchored between the plate 278 and the side wall 12, while the other end of the spring is bent 10 underneath the web guide. I provide the throat 50 of the web guide with a deflecting plate 284 terminating in close relation with the roll 44 to deflect the web into the guide. In threading the web into the guide, roll 44 may be pivoted away 15 from the roll 42 through the medium of a finger 286.

20 Figure 3 illustrates the garment portion 238 as having the label 234 attached thereto by a staple 288. Label 234 is also provided with an identification number 290. During application of the label 234, the edge 292 of the garment lies against the backing plate 190, but the blade 254 severs the web at a safe distance from the edge 292. After placement of the garment on the work support 16 a mere push on the plunger 138 sets the machinery into operation. In one rotation of the shaft 118, the numbering device 200 and the stapling device 244 are moved downwardly together with the severing blade 254. The web is 25 severed to provide the label 234, while the latter is effectively connected with the garment through the medium of the staple 288. At the same time, the label is provided with the identification number 290. The machine stops automatically in that 30 a partial rotation of the shaft 118 will bring the cam face 160 into camming relation with the pin 158 for kicking the trip 134 for opening the 35 circuit through the motor. Thus the garments may be easily and quickly provided with individual labels and the labels numbered in successive 40 numerical order for identification purposes.

45 My device is power operated in such manner as to function efficiently in the performance of its manifold functions. The plunger 138 is so located as to enable the garment or other goods to be manipulated with both hands for positioning purposes, in addition to being advantageously positioned so that one hand may be brought into pressure relation with the plunger for closing the circuit through the motor immediately upon location of the garment. Thus I provide a 50 machine which eliminates foot operated devices and manually actuated levers and the like for applying power. The device functions in such manner as to permit free movement of the operator's feet, and the plunger is so devised as to respond to a slight pressure, in addition to having such location as to substantially render the machine 55 automatic in every respect.

60 The numbering mechanism is connected with a pivoted bar, which pivoted bar actuates the stapling mechanism, which in turn manipulates the severing blade. Thus a single operating connection between the motor and the pivoted bar is 65 sufficient for operating all the mechanisms.

Having thus described certain embodiments of my invention in detail, it is, of course, understood that I do not desire to limit the scope thereof to the exact details set forth except in so far as those 70 details may be defined in the appended claims.

I claim:

1. A device of the type described comprising a work support, a power drive, a web guide including means operatively connected with said power 75

drive for moving the web across work on said work support, means for severing the web to provide a label, a numbering device including a pivoted supporting arm therefor, a stapling mechanism for attaching the label to the work, said stapling mechanism being actuated by said pivoted supporting arm, and the severing device being actuated by said stapling mechanism.

10 2. A device of the type described comprising a work support, a power drive, a web guide including means operatively connected with said power drive for moving the web across work on said work support, means for severing the web to provide a label, a numbering device, a stapling mechanism for attaching the label to the work, means for moving the numbering device and the stapling mechanism down on the label on the work, and said means for severing the web being actuated by said stapling mechanism.

20 3. A device of the type described comprising a work support, an electric motor driven means, a web guide including means operatively connected with said means for moving the web across work on said work support, means for severing the web
25 to provide a label, a numbering device, a stapling mechanism for attaching the label to the work, actuating means for moving the numbering device and the stapling mechanism down on the label on the work, said means for severing the web being actuated by said stapling mechanism, and an operating connection between the first
30 mentioned means and said actuating means.

35 4. A device of the type described comprising a work support, an electric motor driven means, a web guide including means operatively connected with said means for moving the web across work on said work support, means for severing the web to provide a label, a numbering device, a stapling mechanism for attaching the label to the work,
40 actuating means for moving the numbering device and the stapling mechanism down on the label on the work, said means for severing the web being actuated by said stapling mechanism, an operating connection between the first men-
45 tioned means and said actuating means, and a switch for the motor located for manual reach on the work support.

the work support.

5. A device of the type described comprising a work support, a power drive, a web guide including means operatively connected with said power drive for moving the web across work on said work support, means for severing the web to provide a label, a numbering device including a pivoted supporting arm therefor, a stapling mechanism for attaching the label to the work, said stapling mechanism being actuated by said pivoted supporting arm and the severing device being actuated by said stapling mechanism, an electric motor connected with said power drive, and an operating connection between the power drive and said pivoted supporting arm.

6. A device of the type described comprising a work support, a power drive, a web guide including means operatively connected with said power drive for moving the web across work on said work support, means for severing the web to provide a label, a numbering device including a pivoted supporting arm therefor, a stapling mechanism for attaching the label to the work, said stapling mechanism being actuated by said pivoted supporting arm and the severing device being actuated by said stapling mechanism, an electric motor connected with said power drive, an operating connection between the power drive

and said pivoted supporting arm, and a switch for the motor located for manual reach on the work support.

7. A device of the type described comprising a work support, an electric motor driven means, a web guide including means operatively connected with said means for moving the web across work on said work support, means for severing the web to provide a label, a numbering device, a stapling mechanism for attaching the label to the work, actuating means for moving the numbering device and the stapling mechanism down on the label on the work, said means for severing the web being actuated by said stapling mechanism, an operating connection between the first mentioned means and said actuating means, a switch for the motor located for manual reach on the work support, and means actuated by said first means for opening the switch after attachment and numbering of the label. 20

8. A device of the type described comprising a work support, a power drive, a web guide including means operatively connected with said power drive for moving the web across work on said work support, means for severing the web to provide a label, a numbering device including a pivoted supporting arm therefor, a stapling mechanism for attaching the label to the work, said stapling mechanism being actuated by said pivoted supporting arm and the severing device being actuated by said stapling mechanism, an electric motor connected with said power drive, an operating connection between the power drive and said pivoted supporting arm, and means actuated by said first means for opening the switch after attachment and numbering of the label. 25 30 35

9. A device of the type described comprising a work support, a power drive, a web guide including means operatively connected with said power drive for moving the web across work on said work support, means for severing the web to provide a label, a numbering device including a pivoted supporting arm therefor, a stapling mechanism for attaching the label to the work, said stapling mechanism being actuated by said pivoted supporting arm and the severing device being actuated by said stapling mechanism, an electric motor connected with said power drive, an operating connection between the power drive and said pivoted supporting arm, means actuated by said first means for opening the switch after attachment and numbering of the label, and a speed reducer interposed between the motor and the power drive. 40 45 50

10. A device of the type described comprising a work support, an electric motor driven means, a web guide including means operatively connected with said means for moving the web across work on said work support, means for severing the web to provide a label, a numbering device, a stapling mechanism for attaching the label to the work, actuating means for moving the numbering device and the stapling mechanism down on the label on the work, said means for severing the web being actuated by said stapling mechanism, an operating connection between the first mentioned means and said actuating means, and means for braking motor driven means after attachment and numbering of the label. 55 60 65 66

11. A device of the type described comprising a work support, an electric motor driven means, a web guide including means operatively connected with said means for moving the web across work on said work support, means for severing the web to provide a label, a marking device, a stapling means and a transversing of the label. 70

12. A device of the type described comprising a work support, an electric motor driven means, a web guide including means operatively connected with said means for moving the web across work on said work support, means for severing the web to provide a label, a marking device, a stapling means and a transversing of the label. 75

mechanism for attaching the label to the work, actuating means for moving the marking device and the stapling mechanism down on the label on the work, said means for severing the web being actuated by said stapling mechanism, and an operating connection between the first mentioned means and said actuating means.

12. A device of the type described comprising a work support, a power drive, a web guide including means operatively connected with said power drive for moving the web across work on said

work support, means for severing the web to provide a label, a marking device including a pivoted supporting arm therefor, a stapling mechanism for attaching the label to the work, said stapling mechanism being actuated by said pivoted supporting arm and the severing device being actuated by said stapling mechanism, an electric motor connected with said power drive, and an operating connection between the power drive and said pivoted supporting arm.

WENTWORTH S. HINES.

10
